Primary Examiner — Philip S Hyder*Assistant Examiner* — Sydney Buffalow(74) *Attorney, Agent, or Firm* — Saliwanchik, Lloyd & Eisenschenk(57) **CLAIM**

The ornamental design for a tool storage apparatus, as shown and described.

DESCRIPTION

FIG. 1 is a perspective view of a tool storage apparatus. FIG. 2 is a front elevational view of the tool storage apparatus. FIG. 3 is a rear elevational view of the tool storage apparatus. FIG. 4 is a left side view of the tool storage apparatus. FIG. 5 is a right side view of the tool storage apparatus. FIG. 6 is a top plan view of the tool storage apparatus. FIG. 7 is a bottom plan view of the tool storage apparatus. FIG. 8 is a perspective view of the tool storage apparatus with the support arms in an alternative arrangement. FIG. 9 is a front elevational view of the tool storage apparatus shown in FIG. 8. FIG. 10 is a top plan view of the tool storage apparatus shown in FIG. 8; and, FIG. 11 is an exploded perspective view of the tool storage apparatus. The broken line portions are directed to unclaimed subject matter and form no part of the claimed design.
